UNITED STATES PATENT OFFICE

2,127,961

ACTUATOR

William R. Ray, San Francisco, Calif., assignor,
by mesne assignments, to General Controls
Co., a corporation of California

Refiled for abandoned application Serial No.
432,631, March 3, 1930. This application No-
vember 11, 1935, Serial No. 49,271

12 Claims. (CL. 60—52)

This is a refile of my abandoned application
Serial No. 432,631 filed March 3, 1930.

This invention relates to an actuator to control
various devices. More particularly it relates to
5 the provision of a structure in which actuation of
the operative means may be accomplished in ac-
cordance with conditions at a distance from the
structure and, also, so that the movable means
therein returns automatically to a predetermined
10 position.

The structure of my invention has been utilized
particularly with fuel oil burners wherein oil is
supplied under gravity pressure to the burner and
wherein it is desired to control the flow of oil
15 to the burner from a distant point in accordance
with certain conditions at the distant point.

In the control devices previously utilized it has
been the practice to open a valve by means of a
train of gears operated by a suitable source of
20 motive power. When it was desired to make a
change in the valve so that it would lift against
a different oil pressure it was necessary to change
the gear train. This necessitated, usually, the
installation of an entire new valve operating
25 mechanism since the previous mechanism could
not be accommodated to the change. This was
expensive and detracted from the facility of ad-
justing the oil burner to meet conditions. Fur-
ther, actuation of the gear train was accomplished
30 by an electric motor of the "stall" type which
are relatively expensive and increased further
the cost of installation.

It is the general object of my invention to devise
a simple structure for use as an actuator, the
35 operation of which may be initiated and con-
trolled from a distant point.

Another object of the invention is to devise
a structure capable of adjustment so that it
may be adapted to operate under various condi-
40 tions.

The invention possesses other advantageous
features and objects, some of which with the
foregoing will be set forth at length in the fol-
45 lowing description where I shall outline in full
that form of actuator of my invention, which I
have selected for illustration in the drawings
accompanying and forming part of the present
specification. In said drawings I have shown one
50 form of valve actuator embodying my invention,
but it is to be understood that I do not limit
myself to such form since the invention, as set
forth in the claims, may be embodied in a plu-
rality of forms.

In the drawings, to which reference has been
55 made above, Figure 1 is a side elevational view,

partly in section, illustrating a structure embody-
ing certain features of my invention.

Figure 2 is a fragmentary side elevational view
partly in section illustrating the actuating mech-
anism extended to lift a valve. 5

Figure 3 is a cross sectional view taken on the
line 3—3 of Figure 1 but showing another type
of actuatable valve for controlling flow through
a pipe line as compared to that of Figure 1.

Figure 4 is a cross sectional view taken on the 10
line 4—4 of Figure 3.

Figure 5 is a section on the line 5—5 of Fig-
ure 3.

Briefly characterized my invention may be
stated as comprising a self contained structure 15
movable between two extreme positions and nor-
mally biased toward one of these positions so that
it automatically returns to a first position. Ac-
tuation is accomplished by hydraulic means ca-
pable of overcoming the bias placed upon the 20
structure. The device is disclosed in connection
with control of a fuel valve to an oil burner.
However, this is only one use and the actuator
is capable of various applications. 25

With oil burners, oil is supplied to the burner
under pressure. It is usual to control the burner
so that a predetermined temperature may be
maintained at some point. Since it is highly de-
sirable that the burner be shut off almost imme-
diately upon the attaining of this temperature 30
it is expedient that the valve controlling the flow
of oil to the burner be capable of being shut off
positively against the pressure of oil in the line
to the burner. I also prefer that the initiation
of actuation of the valve to allow flow of oil to
35 the burner be of such a nature that it may be
controlled from a distant point. This manner
of operation I have found is accomplished by
suitably biasing the valve to closed position so
that it is positively and automatically forced into
40 engagement with its seat upon failure of the
force holding it open.

The form of valve shown in conjunction with
the actuator comprises a valve body 6 having a
45 seat 7 upon which a soft metallic valve 8 is adapt-
ed to seat to control flow. The valve body 6
may be formed to provide a "straight through"
valve as is shown in Figure 3, or it may include
flow control mechanism such as is shown in Fig-
ure 1 wherein the quantity of fluid passing out
50 of the valve is regulated by the mechanism in-
dicated generally at 11.

Movement of the valve 8 is accomplished
through a rod 12 which extends down through
55 valve body 6 to join the valve through an inter-

mediate member 13 which is joined to the valve 8 to permit a certain amount of movement between them to facilitate seating of the valve. The rod 12 is attached to other mechanisms to be presently described which are capable of moving the valve.

In the particular embodiment illustrated in the drawings I have employed an electric motor 21 as the motor means to actuate the movable mechanism which, in this disclosure, lifts the valve. Other motor means may be employed as a steam, or air driven turbine. Construction of the device is facilitated by providing a hollow casing 22 upon the valve body 6, the two being suitably joined together by studs 23. The motor is positioned upon the casing 22 by a lock nut 24 which engages a threaded portion of the motor and abuts the casing to secure them together, an apertured housing 25 extending about the motor and being positioned on the casing. The motor is provided with a hollow shaft 26 into which a shaft 27 extends and to which it is flexibly joined by pin 28 engaging the hollow shaft. The shaft 27 carries a gear 29 which forms with another gear 31 a gear pump 32 capable of supplying fluid to suitable means for actuating the valve.

A convenient construction for actuating the valve is provided by positioning a piston 30 within the casing 22 so that it is fixed in position and carries the gear pump. A plate 33 secured to the piston retains the gears 29 and 31 in position and serves to provide a pumping chamber within which the gears operate. Rotation of the shaft 27 causes the pump to draw fluid from the fluid reservoir provided by casing 22 and bellows 52. The fluid is forced up through channel 34 and valve 42 in the piston to a chamber 35 formed by cylinder 36 which is positioned within the casing and slidably mounted with respect to the piston. The cylinder carries a yoke 37 which is in turn secured to the rod 12 so that when fluid is supplied to the chamber 35 the valve is lifted.

I have found it desirable to provide for a rapid release of the fluid from the chamber 35 so that the valve 8 may close very quickly. A convenient manner of accomplishing this is provided by drilling the piston to form a cavity 41 within which a shuttle valve 42 is movable to interrupt flow through the channels 34. The cavity 41 is drilled to communicate with the gear pump so that the fluid discharged is effective to move the shuttle valve 42 to a position wherein a communication with the chamber 35 is established through the channels 34. Thus, as is shown in Figure 2, the shuttle valve has been raised from the position shown in Figure 1 so that a passageway 43 in the shuttle valve establishes free communication with the chamber 35. Upon interruption of the supply of current to the motor for any reason as by attaining the desired temperature at the point of control, spring 44 provided upon the shuttle valve is effective to return it to a position shown in Figure 1 wherein free discharge of the fluid in the chamber 35 takes place through several passages in the piston indicated at 46, through groove 47 about the shuttle valve, through passage 48 in the piston to the casing 22.

The valve 8 is automatically returned to closed position upon failure of the power to the motor by a spring 51 positioned between the cylinder and the casing. This spring is of sufficient strength to force the cylinder down. Thus the spring can close the valve 8 against the pressure thereon.

25 I have found that a suitable fluid for use with

the valve is a lubricating oil such as castor oil which is quite satisfactory. In operation, there is sufficient slippage in the pump, and leakage between the cylinder and the piston and out of the cylinder about the shaft so that the motor 5 turns over fairly slowly and does not stall. To have the motor turn over slowly is an advantage since rotation of the motor is effective to draw in a certain amount of air which cools it down, while a stalled motor develops a greater amount of heat. 10 Electric motors commonly include a fan as part of the rotor. This fan is effective to draw in air through an opening in the motor casing and force it out through another opening after the air has passed through the motor.

15 Since it is desirable to employ a particular fluid in the pump it is expedient that admixing of the fluid and the oil supplied to the burner does not take place. I have overcome this difficulty by sealing off the casing 22 from the valve, providing 20 a suitable collapsible metal bellows 52 about the rod 12, the bellows being joined to the member 13 and to a plate 53 positioned between the valve body 6 and the casing 22. The actuator is thus 25 a separate unit.

Upon release of the several studs 23 provided between the valve body and the casing 22, the whole may be disassembled for inspection, repairs or for changing the gears 29 and 31 or spring 51 if it is desired to operate under different conditions.

I claim:

1. An actuator comprising cooperating cylinder and piston members forming a chamber, said cylinder being movable on said piston, a fluid pump on said piston, a motor for operating said pump to supply fluid to the chamber whereby said cylinder is moved relative to said piston in one direction, means for automatically moving said cylinder in an opposite direction to said one direction upon failure of the fluid supply to the chamber, and means operable upon movement of said cylinder in said opposite direction to release fluid from between the cylinder and piston.

2. An actuator comprising a cylinder, a piston fitting in said cylinder, said cylinder being movable on said piston, a fluid pump carried by the piston, a motor for operating the pump, and means carried by the piston for releasing pressure in the cylinder upon failure of power to the motor.

3. An actuator comprising a casing, a motor carried on the casing, a cooperating movable cylinder and a fixed piston within the casing, the casing forming a reservoir, a fluid pump on said piston operable by the motor to withdraw fluid from the reservoir to move the cylinder on the piston, and a valve means carried by the piston and movable between a position in which it releases fluid from between said cylinder and piston and a position in which it directs fluid to be between said cylinder and piston, said valve means being movable in accordance with pressure created by said pump.

4. An actuator movable between two positions comprising a movable cylinder and a fixed piston cooperating to form a chamber, means for supplying fluid under pressure to the chamber to effect movement of said cylinder on said piston, and valve means carried by said piston for controlling fluid flow to and from said chamber, said valve means being operable to release fluid from the chamber upon failure of said supplying means without the fluid passing through said supplying means.

5. An actuator comprising a motor having a

- drive shaft, a casing into which said shaft extends, a member extending from said casing for movement between a first and a second position, means urging said member constantly toward said first position, and means for overcoming said urging means temporarily including a piston, a cylinder in said casing movable on said shaft and on said piston and connected to said member to move said member, means closing said casing to enclose a source of fluid supply, and a gear pump in said piston driven by said motor shaft to force fluid from said source between said cylinder and piston. 5
6. An actuator comprising a motor having a drive shaft, a casing into which said shaft extends, a member extending from said casing for movement between a first and a second position, means urging said member constantly toward said first position, and means for overcoming 10 said urging means temporarily including a piston in said casing, a cylinder movable on said piston and connected to said member to move said member, means closing said casing to enclose a source of fluid supply, and a gear pump in said piston driven by said motor shaft to force fluid from said source between said cylinder and piston. 15

- 25
- 30
- 35
- 40
- 45
- 50
7. An actuator comprising a casing, a motor carried on the casing, a cooperating movable cylinder and a fixed piston within the casing, the casing forming a reservoir, a fluid pump on said piston operable by the motor to withdraw fluid from the reservoir to move the cylinder on the piston, and a valve means carried by the piston and movable between a position in which it releases fluid from between said cylinder and piston and a position in which it directs fluid to between said cylinder and piston, said valve means being movable from said last mentioned position upon loss of pressure from said pump. 40
8. An actuator comprising a casing, a motor carried on the casing, a cooperating movable cylinder and a fixed piston within the casing, the casing forming a reservoir, a fluid pump on said piston operable by the motor to withdraw fluid from the reservoir to move the cylinder on the piston, and a valve means carried by the piston and movable between a position in which it re- 45
- leases fluid from between said cylinder and piston and a position in which it directs fluid to between said cylinder and piston, said valve means being movable from said first mentioned position to said last mentioned position upon creation of pressure by said pump. 5
9. In a device of the character described, a motor, a stationary member, fluid pump means mounted on said member and operable by said motor to deliver fluid under pressure, a movable element in a cylinder-piston structure, means biasing said element in one direction, a passage extending through said member to one side of said movable element to deliver fluid under pressure from said pump into said cylinder-piston structure to move said element against the bias of said means, and valve means in said passage for bypassing said pump to return fluid from said cylinder-piston. 10
- 15
10. In a device of the character described, a motor, a stationary member, fluid pump means mounted on said member and operable by said motor to deliver fluid under pressure, a movable element in a cylinder-piston structure, means biasing said element in one direction, a passage extending through said member to one side of said movable element to deliver fluid under pressure from said pump into said cylinder-piston structure to move said element against the bias of said means, and valve means in said passage for bypassing said pump to return fluid from said cylinder-piston. 20
- 25
- 30
- 35
- 40
- 45
- 50
11. In a device of the character described, a motor, a cylinder and piston structure, a fluid pump operable by said motor to deliver fluid under pressure to said cylinder and piston structure to cause movement of an element of said cylinder and piston structure, means opposing said movement, and means operable upon failure of said motor to by-pass said pump to release fluid from between said cylinder and piston. 40
12. In combination, a valve including a movable valve member, a spring urging said valve member in one direction, a casing structure mounted on said valve, a motor carried by the casing, a fluid pump in said casing, a cylinder and piston structure operable upon fluid delivery from said pump to move said valve member against the urge of said spring, and by-pass means operable upon motor failure to by-pass said pump and release fluid from between the cylinder and piston. 45
